COMBINATION STORM AND SCREEN SASH

Ella May Porter, Shaker Heights, Ohio

Application January 17, 1938, Serial No. 185,450

3 Claims. (Cl. 189—76)

This invention relates to combination storm and screen sash.

The general object of the invention is to provide a combination storm sash of economical construction having readily removable and replaceable interchangeable window and screen panels.

Another object of the invention is to provide a combination storm sash having improved concealed means for securing the sash to the window frame.

Another object of the invention is the provision of novel means for removably latching the window and screen panels in the combination sash.

A still further object of the invention is to provide a weather tight seal between the cross bar of the combination sash and the adjacent lower edge of the glass panel.

Other objects and advantages of the invention will be apparent as the specification is considered with the accompanying drawing, in which:

Figure 1 is a front view of a combination sash showing a fragment of a window frame;

Figure 2 is an enlarged section, partly broken away, taken on the line 2—2 of Figure 1;

Figure 3 is an enlarged section taken on the line 3—3 of Figure 1;

Figure 4 is a section on the line 4—4 of Figure 1; and

Figure 5 is a fragmentary enlarged detail view of one of the sides of the sash frame showing the inclination of the latch receiving slots.

Referring more particularly to the drawing 1 denotes a sash frame of suitable non-corrosive sheet metal comprising sides 2, top and bottom end members 3 and 4 respectively, and a cross member or frame 5, all of which are hollow and preferably welded together at their meeting edges. Removably secured within the sash frame 1, are glass and screen panels 6 and 7 respectively, the glass panel being for winter use and the screen panel being adapted for summer use. These panels are interchangeable and consequently two glass or screen panels, or a glass and a screen panel may be employed, according to the user's desires. The side members 2 of the sash frame 1 are secured to the window casing 8, only one side of which is shown, by means of screws 9. These screws are insertable through openings 10 in the inner wall 11 of the side members 2 and 50 thence into registering openings 12 in the outer wall 13 thereof. The openings 10 are made sufficiently large to permit of the screw heads passing therethrough and also to accommodate a screw driver or the like, not shown. When the panels 55 6 and 7 are placed within the sash frame 1, the

openings 10 as well as the screws 9 will be concealed from view, and it will therefore be difficult for anyone to surreptitiously remove the panels. This serves as a safeguard against theft in addition to making it difficult or impossible for an unauthorized person to enter the building by means of the window without breaking the glass or screen panels. It will of course be understood that the sash frame 1 is screwed to the outside of the window casing 8, to the rear of 10 the usual sliding windows, not shown.

The side members 2 of the frame 1 are formed with rear side flanges 14 against which the panels 6 and 7 rest when inserted in the respective panel openings. The top member 3 of frame 1, is of 15 substantially U-shape to provide a chamber or space 15, in which the upper end of the glass panel 6, is snugly received, the lower end of the panel seating on top of the cross member 5, where it is snugly held between the lower ends of the 20 flanges 14, and a horizontal front flange 16, extending across the top of member 5 at the front thereof. Intermediate frame member 5, like top frame member 3 is of U-shape in cross section thus providing a space 15' for receiving the upper 25 end of the screen panel 7, as best shown in Figure 2 of the drawing. The lower end of panel 7 seats on the bottom cross frame member 4, and is clamped in place between the vertically disposed side flanges 14 on the side members 2 and 30 a horizontal flange 17 at the front of bottom cross member 4.

The glass and screen of panels 6 and 7 are provided with protective borders or frames 18 and 19 of non-corrosive metal, which support and 35 protect the glass or screen and facilitate the attachment of handles 20 and 21 to the panels. To insert a panel in the sash frame 1, it is merely necessary to tilt the panel slightly and slide the upper end thereof into one of the pockets or 40 openings 15 or 15' and then let the panel rest upon either the cross member 5 or cross member 4, according to which panel is being placed. This operation is facilitated by grasping the handles 20 or 21, in an obvious manner. The pockets are 45 sufficiently large and the material from which the frame 1 is made is sufficiently resilient to permit of the panels being forced into the pockets 15 and 15' when held at a slight angle from a vertical position.

Registering openings 22 and 23 extending through the front and back walls of member 4, provide for proper ventilation when a second glass panel 6 is substituted for the screen panel 7. A louvre 24 covers the opening 22 and the latter is 55

also preferably covered by screening 25. A hinged cover for opening 23 is provided for an obvious purpose. The glass pane 26 and screening 27 for panels 6 and 7 can readily be replaced in the respective protective borders or frames 18 and 19, in the event of breakage etc.

The sides 2 of sash frame 1, are provided with latch members 28 one adjacent each of the handles 20 and 21. The members 28 comprise sheet metal strips 29 extending at their inner ends into slots 30, formed in the inner side faces 35 of the sides 2 of frame 1, where they are pivotally mounted by means of studs 31, or the like. These slots are inclined forwardly and upwardly for a purpose hereinafter described. Finger lugs 32 extending at right angles to the strips 29 afford means for swinging the latch members to and from latched position. These lugs also serve as a stop for limiting the pivotal movement of the latch members, when the lugs are seated in notches 33 at the upper extremity of the slots 30, as shown at the right upper portion of Figure 1. With the latches in this position the panels can be readily removed by reversing the assembly operations previously described. To latch the panels in the frame 2, the latch members are swung downwardly to the position shown in the lower half and upper left hand portion of Figure 1. During this movement the latch members 28, due to the inclination of the slots 30, are forced to engage the front faces of the border members 18 and 19 with cam effect.

In order to provide a tight seal against the entrance of snow and rain at the joint 34 between the lower end of the panel 6 and the upper end of cross member 5, a metallic strip 35 is provided

between these two adjacent parts, secured as by welding to the member 5. This strip 35 is formed with a downwardly bent flange 36 which effectively sheds rain and snow from the joint 34.

What I claim is:

1. A storm window comprising a metal sash frame having hollow side and cross members defining panel openings, panels fitting snugly in said openings, the side members of sash frame having cam slots therein, latch members pivotally mounted in said slots and movable outwardly therefrom into latching engagement with said panels. 5

10 15 20 25 30 35

2. Means for latching windows having hollow frame members defining panel openings for the reception of panels, comprising latch members pivoted at one end to said hollow frame members, for movement into and out of slots formed in said frame members and into and out of engagement with said panels to latch and unlatch said panels, and an offset portion on said latch members to facilitate operation of the latch member and to serve as a stop. 20

3. Means for latching windows having hollow frame members defining panel openings for the reception of panels, comprising latch members pivoted at one end to said hollow frame members for movement into and out of upwardly and forwardly inclined slots formed in said frame members and into and out of engagement with said panels to latch and unlatch said panels and an offset portion on said latch members to facilitate operation of the latch member and to serve as a stop. 25 30 35
